STABILIZATION OF ORGANIC COMPOUNDS

Joseph A. Chenicek, Bensenville, and Ralph B. Thompson, Hinsdale, Ill., assignors to Universal Oil Products Company, Chicago, Ill., a corporation of Delaware

No Drawing. Application May 31, 1951,
Serial No. 229,266

24 Claims. (Cl. 99—163)

1

This application is a continuation-in-part of our copending application Serial No. 4,079 filed January 23, 1948, now abandoned.

This invention relates to the stabilization of organic compounds which tend to deteriorate in storage or in use due to oxidation reactions.

Various organic compounds are unstable in storage or during treatment and form undesirable gums, undergo discoloration, form sludges or otherwise deteriorate due to oxidation, polymerization or other undesired reactions. Included among the organic compounds which undergo such deterioration and which are intended for treatment according to the present invention are gasoline, diesel oil, mineral oil, lubricating oil, fuel oil, drying oil, greases, edible fats and oils, acetylenes and particularly vinyl acetylene, butadiene, isoprene, styrene and other vinyl aromatics, various unsaturated alcohols, acids, ketones, etc.

The invention is particularly applicable to the stabilization of unsaturated gasolines and particularly cracked and polymer gasolines. In storage or during treatment these unsaturated gasolines tend to form undesirable gums. The invention is also applicable to the treatment of aviation gasolines which tend to undergo deterioration due to the addition of tetraethyl lead fluid or due to other components in the gasoline.

The invention is also particularly applicable to the stabilization of edible fats and oils which generally are of animal or vegetable origin and which tend to become rancid, especially during long periods of storage prior to use. Typical representatives of these edible fats and oils include linseed oil, menhaden oil, cod liver oil, castor oil, olive oil, rapeseed oil, coconut oil, palm oil, corn oil, sesame oil, peanut oil, babassu oil, butter, fat, lard, beef tallow, etc. It is understood that other oils and fats may be treated within the scope of the present invention, including oils and fats which have previously been subjected to various treatments, such as blowing with air, heat treatment, etc.

In another embodiment the present invention is particularly applicable to the treatment of crops by dusting or spraying in order to preserve food accessory factors such as carotene, vitamins, various fatty acids, alcohols, etc.

In one embodiment the present invention relates to a method of stabilizing an organic material subject to oxidative deterioration which comprises adding thereto a monoalkyl ether of a dihydroxy- di- or tetrahydronaphthalene.

In another embodiment the present invention relates to a method of stabilizing an organic material subject to oxidative deterioration which

2

comprises adding thereto a monoalkyl ether of a 1,4-dihydroxy- di- or tetrahydronaphthalene. In a specific embodiment the present invention relates to a method of stabilizing motor fuel normally tending to deteriorate in storage which comprises adding thereto from about 0.001% to about 0.5% by weight of 1-hydroxy-4-methoxy-5,8-dihydronaphthalene.

In another specific embodiment the present invention relates to a method of stabilizing edible fats and oils against rancidity which comprises adding thereto from about 0.001% to about 0.5% by weight of 1-hydroxy-4-methoxy-7-methyl-5,8-dihydronaphthalene.

In another embodiment the present invention relates to motor fuel normally tending to deteriorate in storage containing, as an inhibitor for said deterioration, a small amount of a 1-hydroxy-4-alkoxy-5,8-dihydronaphthalene or a 1-hydroxy-4-alkoxy-5,6,7,8-tetrahydronaphthalene.

In another embodiment the present invention relates to edible fats and oils normally tending to become rancid containing a 1-hydroxy-4-alkoxy-5,8-dihydronaphthalene or a 1-hydroxy-4-alkoxy-5,6,7,8-tetrahydronaphthalene in an amount sufficient to retard rancidity development.

In accordance with the invention, stabilization of unstable organic compounds is effected by adding thereto a small amount of a monoalkyl ether of dihydroxy-5,8-dihydronaphthalene or of dihydroxy-5,6,7,8-tetrahydronaphthalene. It has been found that these monoalkyl ethers unexpectedly are of high potency in preventing deterioration of organic compounds. As will be shown in the following examples, these monoalkyl ethers exhibit extremely high potency in contrast to the low and in many cases no inhibitor potency for the corresponding dihydroxynaphthalenes, monoalkyl ethers of dihydroxynaphthalenes, dihydroxy-hydronaphthalenes and the dialkyl ethers of dihydroxynaphthalenes and dihydroxy-hydronaphthalenes. These extremely high potencies exhibited by the monoalkyl ethers of the dihydroxy-hydronaphthalenes are surprising in view of the fact that the compounds as mentioned above, which might be considered somewhat similar to the compounds of the present invention, either are of low effect or substantially of no effect as inhibitors, as well as the fact that the etherification of the monocyclic dihydroxyphenols, as will be shown in the following examples, actually decreases the inhibitor potency. Therefore, in the absence of the teachings of the present application, one would be led away from the etherification of the dihydroxynaphthalene in a desire to obtain active inhibitor. Furthermore, it has been found that these monoalkyl ethers are

considerably more soluble in organic compounds than the corresponding dihydroxynaphthalene and, therefore, these ether compounds are particularly suitable for use as inhibitors.

The preferred inhibitors of the present invention may be represented by the following general structures:

Structure I illustrates 1-hydroxy-4-alkoxy-5,8-dihydronaphthalene and structure II illustrates 1-hydroxy-4-alkoxy-5,6,7,8-tetrahydronaphthalene.

Referring to the general structure illustrated above, H comprises hydrogen and R comprises an alkyl radical preferably containing from 1 to about 8 carbon atoms and therefore includes alkyl groups such as methyl, ethyl, propyl, butyl, amyl, hexyl, heptyl and octyl. Still more particularly, R preferably comprises an alkyl group containing from 1 to 4 carbon atoms and includes such groups as ethyl, methyl, propyl and butyl. This is particularly true when 1 or both of the rings are substituted with alkyl groups in the manner to be hereinafter set forth, in order that the total number of carbon atoms does not exceed about 25 and preferably 20.

As hereinbefore set forth, one or both of the rings may be substituted with alkyl group or groups. Preferably each alkyl group should not contain more than about 5 carbon atoms in order that the total number of carbon atoms in the inhibitor does not exceed about 25 and still more preferably does not exceed about 20. Preferred alkyl groups include ethyl, methyl, propyl, tertiary butyl and tertiary amyl radicals.

Preferred inhibitors of the present invention include, 1-hydroxy-4-methoxy-5,8-dihydronaphthalene, 1-hydroxy-4-ethoxy-5,8-dihydronaphthalene, 1-hydroxy-4-propoxy-5,8-dihydronaphthalene, 1-hydroxy-4-butoxy-5,8-dihydronaphthalene, 1-hydroxy-4-methoxy-7-methyl-5,8-dihydronaphthalene, 1-hydroxy-4-ethoxy-7-methyl-5,8-dihydronaphthalene, 1-hydroxy-4-propoxy-7-methyl-5,8-dihydronaphthalene, 1-hydroxy-4-butoxy-7-methyl-5,8-dihydronaphthalene, 1-hydroxy-4-methoxy-5,7-dimethyl-5,8-dihydronaphthalene, 1-hydroxy-4-ethoxy-5,7-dimethyl-5,8-dihydronaphthalene, 1-hydroxy-4-propoxy-5,7-dimethyl-5,8-dihydronaphthalene, 1-hydroxy-4-butoxy-5,7-dimethyl-5,8-dihydronaphthalene, 1-hydroxy-4-methoxy-5,6,7,8-tetrahydronaphthalene, 1-hydroxy-4-ethoxy-5,6,7,8-tetrahydronaphthalene, 1-hydroxy-4-propoxy-5,6,7,8-tetrahydronaphthalene, 1-hydroxy-4-butoxy-5,6,7,8-tetrahydronaphthalene, 1-hydroxy-4-methoxy-5,6,7,8-tetrahydronaphthalene, 1-hydroxy-4-ethoxy-5,6,7,8-tetrahydronaphthalene, 1-hydroxy-4-propoxy-5,6,7,8-tetrahydronaphthalene, 1-hydroxy-4-butoxy-5,6,7,8-tetrahydronaphthalene, and 1-hydroxy-4-butoxy-5,7-dimethyl-5,6,7,8-tetrahydronaphthalene.

It will be noted that the preferred inhibitors include the 1-hydroxy-4-alkoxy-di- and tetrahydronaphthalenes, as well as those in which an alkyl group or groups are attached in the 5 or 5 and 7 positions. While these are the preferred compounds it is understood that substitution of alkyl group or groups in other positions on either or both of the rings are included within the scope of the present invention.

It is understood that the inhibitors of the present invention may comprise the specific compounds named herein in admixture with various isomers thereof. For example, in the dihydro compounds, the isomers may comprise corresponding compounds in which the double bond has shifted from the 6-7 position to the 5-6 or 7-8 positions, and/or those in which the hydroxy and alkoxy groups have interchanged positions with respect to an alkyl group. In the tetrahydro compounds, the isomers will be of the latter type.

The inhibitors of the present invention may be prepared in any suitable manner. In one method of preparing 1-hydroxy-4-methoxy-dihydronaphthalene, butadiene is reacted with p-benzoquinone. The p-benzoquinone is preferably dissolved in a suitable organic solvent such as alcohol, benzene, toluene, etc. The reaction readily proceeds at room temperature with the evolution of heat. After the reaction has been completed, the product is purified by recrystallization from organic solvents and then is dissolved in acetic acid and a few drops of hydrobromic acid are added to effect isomerization to the dihydroaromatic structure. The product may be recrystallized from organic solvents and then reacted with dimethyl sulfate to form the desired ether. The monoether is separated by extracting with Claisen solution and then is purified by distillation under vacuum. When the ethyl ether is desired, diethyl sulfate is used instead of dimethyl sulfate. Similarly, when 1-hydroxy-4-methoxy-7-methyl-dihydronaphthalene is desired, isoprene is used in place of butadiene. When the 5,7 di-substituted compound is desired, 2-methyl pentadiene is utilized in its preparation.

1-hydroxy-4-methoxy-5,6,7,8-tetrahydronaphthalene may be prepared by dissolving 1,4-dihydroxy-5,8-dihydronaphthalene in a suitable solvent, such as ethyl acetate, and reducing with hydrogen in the presence of a suitable catalyst such as palladium on calcium carbonate. The desired ether may be formed by reacting with dimethyl sulfate, diethyl sulfate, etc. in the manner hereinbefore set forth.

When it is desired to add other alkyl group or groups to either one or both of the rings, it may be effected in any suitable manner. For example, butylation may be effected by dissolving the 1-hydroxy-4-alkoxy di- or tetrahydronaphthalene in acetic acid and adding thereto a suitable catalyst such as 85% phosphoric acid. Tertiary butyl alcohol is then added and the mixture may be heated to a temperature of 60-85°C. with constant stirring, after which the product may be poured into water, extracted first with organic solvents and then with Claisen solution and finally distilled in vacuum.

The inhibitor of the present invention is generally added to organic materials in an amount of less than 1% by weight and generally within the range of from about 0.001% to about 0.5%. When used in gasoline, it is understood that the inhibitor may be used in conjunction with various dyes, synergists, metal deactivators, antiknock

agents such as tetraethyl lead, etc. When used in edible fats and oils it is understood that the inhibitor may be used in conjunction with a synergist, such as phosphoric acid, ascorbic acid, citric acid, etc.

The following examples are introduced to illustrate further the novelty and utility of the present invention but not with the intention of unduly limiting the same.

The inhibitors used in the following runs were prepared in a manner similar to that heretofore set forth.

EXAMPLE I

The following runs were made with a lard which had a normal stability period of 3½ hours as determined by the Swift test. This test is described in detail in the article by A. E. King, H. L. Roschen and W. H. Irwin, which appeared in the Oil and Soap, vol. X, No. 6, pages 105 to 109 (1933). In general, this test comprises bubbling air through a sample of the lard and reporting the number of hours until the lard develops a peroxide value of 20.

Inhibitor in concentrations of 0.02% by weight was added to different samples of the lard and gave the results as shown in Table 1.

Table 1

Inhibitor	Stability Period, Hours
1-hydroxy-4-methoxy-5,8-dihydronaphthalene	67
1-hydroxy-4-ethoxy-5,8-dihydronaphthalene	60
1-hydroxy-4-methoxy-7-methyl-5,8-dihydronaphthalene	66
1-hydroxy-4-ethoxy-7-methyl-5,8-dihydronaphthalene	80
1-hydroxy-4-methoxy-5,6,7,8-tetrahydronaphthalene	36
1-hydroxy-4-ethoxy-5,6,7,8-tetrahydronaphthalene	37
1-hydroxy-4-methoxy-7-methyl-5,6,7,8-tetrahydronaphthalene	41
Above compound butylated	45
1-hydroxy-4-ethoxy-7-methyl-5,6,7,8-tetrahydronaphthalene	41
1-hydroxy-4-methoxy-5,7-dimethyl-5,6,7,8-tetrahydronaphthalene	40
1-hydroxy-4-ethoxy-5,7-dimethyl-5,6,7,8-tetrahydronaphthalene	45
	39

It will be noted from the data in the above table that the various inhibitors of the present invention considerably increased the stability period of the lard.

EXAMPLE II

The following tests were made with a Pennsylvania cracked gasoline which had an uninhibited induction period of 100 minutes. 0.025% by weight of inhibitor was added to different samples of the gasoline and gave the results as shown in Table 2.

Table 2

Inhibitor	Induction Period, Minutes
1-hydroxy-4-methoxy-5,8-dihydronaphthalene	880
1-hydroxy-4-ethoxy-5,8-dihydronaphthalene	950
1-hydroxy-4-methoxy-7-methyl-5,8-dihydronaphthalene	790
1-hydroxy-4-ethoxy-7-methyl-5,8-dihydronaphthalene	865
1-hydroxy-4-methoxy-5,7-dimethyl-5,8-dihydronaphthalene	805
1-hydroxy-4-ethoxy-5,7-dimethyl-5,8-dihydronaphthalene	65
1-hydroxy-4-methoxy-5,6,7,8-tetrahydronaphthalene	810
1-hydroxy-4-ethoxy-5,6,7,8-tetrahydronaphthalene	885
1-hydroxy-4-methoxy-7-methyl-5,6,7,8-tetrahydronaphthalene	890
1-hydroxy-4-ethoxy-7-methyl-5,6,7,8-tetrahydronaphthalene	790
1-hydroxy-4-ethoxy-7-methyl-5,6,7,8-tetrahydronaphthalene	810
1-hydroxy-4-methoxy-5,7-dimethyl-5,6,7,8-tetrahydronaphthalene	855
1-hydroxy-4-ethoxy-5,7-dimethyl-5,6,7,8-tetrahydronaphthalene	800

It will be noted from the data in the above

table that the inhibitors of the present invention considerably increased the induction periods of the gasoline.

EXAMPLE III

For comparative purposes, 0.025% by weight of a corresponding dihydroxy-5,8-dihydronaphthalene and of a corresponding dimethoxy-dihydronaphthalene were tested in other samples of the cracked gasoline used in Example II. The results of these tests are shown in Table 3.

Table 3

Inhibitor	Induction Period, Minutes
1,4-dihydroxy-5,7-dimethyl-5,8-dihydronaphthalene	100
1,4-dimethoxy-7-methyl-5,8-dihydronaphthalene	100

It will be noted that the dihydroxynaphthalene and the dimethoxynaphthalene had no effect at all in improving the induction period of the cracked gasoline. On the other hand, the corresponding 1-hydroxy-4-methoxy-5,7-dimethyl-5,8-dihydronaphthalene increased the induction period from 100 to 805 minutes and the corresponding 1-hydroxy-4-methoxy-7-methyl-5,8-dihydronaphthalene increased the induction period from 100 to 790 minutes.

EXAMPLE IV

As hereinbefore set forth the monoalkyl ethers of the dihydroxy-hydronaphthalenes are of unexpectedly higher potency than the corresponding dihydroxynaphthalenes, the dihydroxy-hydronaphthalenes, the monoalkyl ethers of dihydroxynaphthalenes, the dialkyl ethers of dihydroxynaphthalenes and the dialkyl ethers of dihydroxyhydronaphthalenes. Table 4 shows the results obtained in the stabilization of lard when using dihydroxynaphthalenes and dihydroxy-tetrahydronaphthalenes, as well as the results obtained when using the monoalkyl ethers of the hydronaphthalenes of the present invention.

Table 4

No.	Compound	Stability Period, Hours
50	None	3½
1	Dihydroxynaphthalenes:	
2	1,4-dihydroxynaphthalene	less than 22.
	2-methyl-1,4-dihydroxynaphthalene	less than 18.
55	Dihydroxy-tetrahydronaphthalenes:	
3	1,4-dihydroxy-5,6,7,8-tetrahydronaphthalene	16-21.
	1,4-dihydroxy-7-methyl-5,6,7,8-tetrahydronaphthalene	less than 20.
	1,4-dihydroxy-5,7-dimethyl-5,6,7,8-tetrahydronaphthalene	less than 21.
50	Monoalkyl ethers of dihydronaphthalene:	
4	1-hydroxy-4-methoxy-5,8-dihydronaphthalene	67.
	1-hydroxy-4-ethoxy-5,8-dihydronaphthalene	60.
4	1-hydroxy-4-methoxy-7-methyl-5,8-dihydronaphthalene	66.
	1-hydroxy-4-ethoxy-7-methyl-5,8-dihydronaphthalene	80.
5	Monoalkyl ethers of tetrahydronaphthalene:	
	1-hydroxy-4-methoxy-5,6,7,8-tetrahydronaphthalene	36.
	1-hydroxy-4-ethoxy-5,6,7,8-tetrahydronaphthalene	37.
	1-hydroxy-4-methoxy-7-methyl-5,6,7,8-tetrahydronaphthalene	41.
	1-hydroxy-4-ethoxy-7-methyl-5,6,7,8-tetrahydronaphthalene	45.

The reason that the stability period in hours is reported as less than a given number or as a range of two numbers is because the sample reached a peroxide value of 20 during the night,

at which time an operator was not present to record the exact hourly reading.

It will be noted that dihydroxynaphthalene or dihydroxy-tetrahydronaphthalene, as well as alkylated derivatives thereof, as represented by classes 2 and 3, stabilized the lard for periods of less than 22 hours. In contrast thereto inhibitors prepared in accordance with the present invention, as represented by classes 4 and 5, increased the stability period to over 36 hours as shown by the data in the above table.

Table 4 represents the results obtained in the stabilization of lard using the various compounds set forth above, as well as the monoalkyl ethers of the dihydroxy-hydronaphthalenes of the present invention. The lard used was the same as that used in Example 1, and the various compounds were used in the same concentration of 0.02% by weight.

EXAMPLE V

The following data were obtained in the stabilization of a lard having a normal stability period of 5 hours, and compares the results obtained by the use of 1-hydroxy-4-ethoxy-7-methyl-5,8-dihydronaphthalene with the results obtained when using 1,4-dihydroxy-7-methyl-5,8-dihydronaphthalene. These compounds were used in a concentration of 0.02% by weight.

Table 5.

No.	Compound	Stability Period, Hours
6.	None.	5
7.	1,4-dihydroxy-7-methyl-5,8-dihydronaphthalene.	23
8.	1-hydroxy-4-ethoxy-7-methyl-5,8-dihydronaphthalene.	78

It will be noted that the monoalkyl ether compound resulted in a stability period of greater than three times that obtained by the corresponding dihydroxy compound.

EXAMPLE VI

This example shows a similar comparison as shown in Examples IV and V using these inhibitors in cracked gasoline. The gasoline used in this example was the same as that used in Example II and the compounds similarly were used in a concentration of 0.025% by weight.

Table 6

No.	Compound	Induction Period, Minutes
9.	None.	100
10.	Dihydroxynaphthalene: 2-methyl-1,4-dihydroxynaphthalene.	80
11.	Dihydroxy-dihydronaphthalene: 1,4-dihydroxy-7-methyl-5,8-dihydronaphthalene.	100
12.	Monalkyl ether of dihydroxynaphthalene: 1-hydroxy-2-methyl-4-methoxy naphthalene.	315
13.	Dialkyl ether of dihydronaphthalene: 2-methyl-1,4-dimethoxy naphthalene.	125
14.	Dialkyl ether of dihydroxy dihydronaphthalene: 1,4-dimethoxy-7-methyl-5,8-dihydronaphthalene.	100
15.	Monalkyl ethers of dihydronaphthalenes: 1-hydroxy-4-methoxy-5,8-dihydronaphthalene.	880
16.	1-hydroxy-4-ethoxy-5,8-dihydronaphthalene.	950
	1-hydroxy-4-methoxy-7-methyl-5,8-dihydronaphthalene.	790
	1-hydroxy-4-ethoxy-7-methyl-5,8-dihydronaphthalene.	865
	Monalkyl ethers of tetrahydronaphthalene: 1-hydroxy-4-methoxy-5,6,7,8-tetrahydronaphthalene.	70
	1-hydroxy-4-ethoxy-5,6,7,8-tetrahydronaphthalene.	885
	1-hydroxy-4-ethoxy-5,6,7,8-tetrahydronaphthalene.	890

In the interest of brevity, only representative compounds are reported for the various classes in the above table. These results are typical of those obtainable with compounds in these classes.

- 5 In contrast to the poor results obtained with compounds of classes 10 to 14 inclusive, exceptionally high inhibitor potencies were obtained with the compounds of the present application as represented by compounds of classes 15 and 16.
 10 For a more specific comparison, note particularly the results obtained with compounds of classes 11 and 14 as compared to the results obtained with the third compound of class 15 wherein the former compounds show no inhibitor potency and 15 the latter compound shows a high potency.

EXAMPLE VII

From the data heretofore presented, it is noted that the monoalkyl ethers of dihydroxy-hydronaphthalenes are of unexpectedly high potency for use as inhibitors in the stabilization of organic compounds. These high potencies are all the more surprising because etherification of the dihydroxy-monocyclic aromatic compounds serves to decrease the inhibitor potency in contrast to the high increase obtained by etherification of the polycyclic compounds. Table 7 presents data on the results obtained when using hydroquinone, as representative of the dihydroxymonocyclic aromatic compounds, and when using ethers of hydroquinone. These tests were made using lard which had a normal stability period of 1 1/4 hours. The compounds in these tests were utilized in an amount of 0.005% by weight.

Table 7

No.	Compound	Stability Period, Hours
40	None.	1 1/4
17.	Hydroquinone.	25
18.	Hydroquinone monomethylether.	6
19.	Hydroquinone monoethyl ether.	7

- 45 It will be noted that converting hydroquinone to the ether considerably reduced the inhibitor potency of the compound. In contrast to this, it will be noted from the data presented in Examples IV, V and VI that converting dihydroxy-hydronaphthalene to the monoether considerably increased the inhibitor potency. As hereinbefore set forth, the latter result is surprising in view of the former result.

We claim as our invention:

- 55 1. A method of stabilizing an organic material normally subject to oxidative deterioration which comprises adding thereto an inhibitor comprising a monoalkyl ether of a dihydroxy-hydronaphthalene in an amount sufficient to retard said deterioration.
- 60 2. A method of stabilizing an organic material normally subject to oxidative deterioration which comprises adding thereto a monoalkyl ether of a 1,4-dihydroxy-5,8-dihydronaphthalene in an amount sufficient to retard said deterioration.
- 65 3. A method of stabilizing an organic material normally subject to oxidative deterioration which comprises adding thereto a monoalkyl ether of a 1,4-dihydroxy-5,6,7,8-tetrahydronaphthalene in an amount sufficient to retard said deterioration.
- 70 4. A method of stabilizing gasoline normally tending to deteriorate in storage which comprises adding thereto a monoalkyl ether of a 1,4-dihydroxy-5,8-dihydronaphthalene in an amount sufficient to retard said deterioration.

5. A method of stabilizing gasoline normally tending to deteriorate in storage which comprises adding thereto a monoalkyl ether of a 1,4-dihydroxy - 5,6,7,8 - tetrahydronaphthalene in an amount sufficient to retard said deterioration.

6. A method of stabilizing cracked gasoline which comprises adding thereto from about 0.001% to about 0.5% by weight of 1-hydroxy-4-ethoxy-5,8-dihydronaphthalene.

7. A method of stabilizing cracked gasoline which comprises adding thereto from about 0.001% to about 0.5% by weight of 1-hydroxy-4-methoxy-5,6,7,8-tetrahydronaphthalene.

8. A method of stabilizing cracked gasoline which comprises adding thereto from about 0.001% to about 0.5% by weight of 1-hydroxy-4-ethoxy-5,6,7,8-tetrahydronaphthalene.

9. A method of stabilizing edible fats and oils normally tending to deteriorate in storage which comprises adding thereto a monoalkyl ether of a 1,4 - dihydroxy - 5,8 - dihydronaphthalene in an amount sufficient to retard said deterioration.

10. A method of stabilizing edible fats and oils normally tending to deteriorate in storage which comprises adding thereto a monoalkyl ether of a 1,4-dihydroxy-5,6,7,8-tetrahydronaphthalene in an amount sufficient to retard said deterioration.

11. A method of stabilizing edible fats and oils against rancidity which comprises adding thereto from about 0.001% to about 0.5% by weight of 1-hydroxy - 4 - methoxy - 7 - methyl - 5,8 - dihydronaphthalene.

12. An organic material normally subject to oxidative deterioration containing, as an inhibitor for said deterioration, a monoalkyl ether of a dihydroxy-hydronaphthalene in an amount sufficient to retard said deterioration.

13. An organic material normally subject to oxidative deterioration in storage containing, as an inhibitor for said deterioration, from about 0.001% to about 0.5% by weight of a monoalkyl ether of a 1,4-dihydroxy-5,8-dihydronaphthalene.

14. An organic material normally subject to oxidative deterioration in storage containing, as an inhibitor for said deterioration, from about 0.001% to about 0.5% by weight of a monoalkyl ether of a 1,4-dihydroxy-5,6,7,8-tetrahydronaphthalene.

15. Cracked gasoline containing from about 50

0.001% to about 0.5% by weight of 1-hydroxy-4-ethoxy-5,8-dihydronaphthalene.

16. Cracked gasoline containing from about 0.001% to about 0.5% by weight of 1-hydroxy-4-methoxy-5,6,7,8-tetrahydronaphthalene.

17. Cracked gasoline containing from about 0.001% to about 0.5% by weight of 1-hydroxy-4-ethoxy-5,6,7,8-tetrahydronaphthalene.

18. Edible fats and oils normally tending to become rancid containing from about 0.001% to about 0.5% by weight of 1-hydroxy-4-methoxy-7-methyl-5,8-dihydronaphthalene.

19. Edible fats and oils normally tending to become rancid containing from about 0.001% to about 0.5% by weight of 1-hydroxy-4-ethoxy-7-methyl-5,8-dihydronaphthalene.

20. Lard normally tending to become rancid containing from about 0.001% to about 0.5% by weight of 1-hydroxy-4-ethoxy-7-methyl-5,8-dihydronaphthalene.

21. An organic material normally subject to oxidative deterioration containing, in sufficient amount to retard said deterioration, a monoalkyl ether of a dihydroxy-hydronaphthalene in which said alkyl radical contains from 1 to about 8 carbon atoms.

22. Gasoline normally subject to oxidative deterioration containing, in sufficient amount to retard said deterioration, a monoalkyl ether of a dihydroxy-hydronaphthalene in which said alkyl radical contains from 1 to about 8 carbon atoms.

23. A fatty material normally subject to oxidative deterioration containing, in sufficient amount to retard said deterioration, a monoalkyl ether of a dihydroxy-hydronaphthalene in which said alkyl radical contains from 1 to about 8 carbon atoms.

24. Lard normally subject to oxidative deterioration containing, in sufficient amount to retard said deterioration, a monoalkyl ether of a dihydroxy-hydronaphthalene in which said alkyl radical contains from 1 to about 8 carbon atoms.
